LOW PRESSURE FUEL BURNER

Richard K. McConnell, Oklahoma City, Okla., assignor to Phillips Petroleum Company, a corporation of Delaware

Application July 27, 1936, Serial No. 92,886

1 Claim. (CL 158—104)

The present invention relates to fuel burners, and more particularly to low pressure burners for gaseous fuels.

Present day fuel burners employing gaseous substances as the combustible medium, and known to applicant, require relatively high gas pressures for their satisfactory and efficient operation. Pressures from 15 pounds per square inch and up are generally required.

10 In many instances, however, the available gas pressure is much lower than the minimum pressure of 15 pounds per square inch, thus resulting in inefficient and unsatisfactory burner operation, and in many instances, when extremely low pressures are encountered, the inefficiency is so pronounced that furnace temperatures or boiler steam pressures cannot be maintained.

15 It is of course obvious that a result such as above described requires that the gas pressure be raised which in turn raises the cost of gas to the operator.

20 In well drilling in particular, low gas pressures are frequently encountered thereby causing serious losses to the drilling contractor who must have adequate steam pressure at all times to return a profit. Cessation of drilling operations even for a short time while awaiting adequate steam pressure means a substantial loss to the contractor and may mean a subsequent loss to the producer if the well is not completed in time.

25 It is therefore an object of the present invention to provide a burner requiring relatively low gas pressures for efficient operation.

30 Another object of the present invention is to provide a gas burner in which a satisfactory mixture of gas and air may be obtained even at low operating pressures.

35 A still further object of the present invention is to provide a burner of simple construction, economical and easy to operate and of low cost.

40 Other objects and advantages of applicant's invention will be apparent from a consideration of the specification in conjunction with the accompanying drawing forming a part thereof, in which

45 Fig. 1 is an isometric view of the burner.

Fig. 2 is a sectional view, taken on the line 2—2 of Fig. 1, looking in the direction of the arrows.

50 Referring particularly to Fig. 1, 10 indicates a burner section which may be employed as a single unit or may be used in conjunction with other sections to form a burner block. An individual section, or a series of such interconnected sections may be installed in the firebox

and cemented in a wall thereof in such manner that one face is exposed to the furnace exterior and the other faces the firebox interior. The burners may be placed in an upright position, a horizontal position, or in any other position dictated by the type of furnace or boiler in which the burner is to be used, it being understood that the burner will operate in any position. A burner body or frame is indicated at 11 which is hollow to provide a fuel chamber 14 (Fig. 2), provided with sides 11' and faces 12 and 13, which is in communication with another burner section or with a source of supply, through the conduits 15, which in the present instance are indicated as nipples provided with screwthreads 16. While 19 the burner body 11 is shown as of box-like configuration, it is obvious that other shapes may be substituted. A series of oppositely disposed apertures 17 in the faces 12 and 13, connected by tubular members 18, form fuel mixing conduits 20 in which gas and air are properly intermixed prior to combustion. Each of these conduits is provided with a cylindrical portion 21 extending for a portion of its length, and which terminates in an abrupt shoulder 22 which in turn joins with a tapered portion 23 terminating in the burner face 12. A fuel jet or port 24 in the form of a bore extending through the wall of each of the tubular members 18 at an acute angle to the axis thereof, terminates in the shoulder 22 and serves to inject gas from the chamber 14 into the mixing conduit 20 in such a manner and at such an angle that the direction of flow will intersect the axis of the mixing conduit at a point within the tapered portion 23 but adjacent the flame opening in the face 12, whereby a thorough mixing of gas and air is obtained even though the gas pressure is of a low order.

25 It is to be understood that the burner may be cast or otherwise formed, and that the jets 24 40 may be drilled through the conduit walls after completion of the body portion.

In operation a burner section or a series of interconnected burner sections are sealed into the firebox opening with cement so that the face 45 12 faces the interior and the face 13, the exterior of the firebox. It will now be evident that air for supporting combustion must pass through the burner apertures 17 and the mixing conduits 20 under the influence of the furnace draft. As 50 this air passes through the conduits 20, it is intermixed with the proper portion of gas issuing from the jet 24. Thorough mixing is accomplished by conducting the air, at the point of gas admission, through the tapered portion 23 of the 55

conduit 20 whereupon its velocity is first decreased due to the conduit enlargement caused by the shoulder 22 and then increased uniformly to the point of egress. Some turbulence occurs 5 at the shoulder 21 which aids in the mixing and which is smoothed out prior to combustion by the tapered portion 23. The proper gas ratio is determined by the diameter of the jets 24 which may vary in accordance with the size of 10 the burner. Combustion occurs immediately upon egress of the mixture from the mixing conduits with the production of an intense blue flame.

In some instances, additional air may be supplied by cementing the burner block loosely in 15 the firebox opening.

Applicant's burner has proved its efficacy on pressures as low as 0.5 pound per square inch and excellent results are obtained on pressures 20 of from 1 to 3 pounds. On actual installations, not only have burners embodying the present invention operated successfully on gas pressures within the range above stated, but more complete mixing as indicated by flue gas analyses and increased boiler ratings over replaced high pressure burners indicate the desirability of utilizing 25 burner of this type operating at low pressure, in many installations, even when high pressure gas is available. In actual tests it has been determined that applicant's burner consumes about 30

18% less fuel per B. H. P. than the burner previously used and the developed B. H. P. was increased 25%

The foregoing specification and drawing forming 5 a part thereof describe a preferred embodiment of my invention, but it is to be understood that applicant intends to limit his invention only by the scope of the subjoined claim.

Having thus described my invention, I claim:

In a low pressure gas burner for firing a boiler, 10 a hollow body forming a gas chamber for the reception of gas from a source, a conduit defined by walls extending through said chamber from one side of said body to the other, said conduit thus presenting an entrance at one side of said body and an exit at the other side of said body, 15 said conduit having a portion of uniform cross section extending inwardly from said entrance to a point intermediate its length, said conduit being enlarged at this point to present a shoulder, 20 said conduit walls tapering from said shoulder to said exit, a bore in said walls connecting said gas chamber and said conduit, said bore opening in said conduit in a port located on said shoulder, the direction of said bore being such that a line 25 therethrough extended, intersects the axis of the tapered conduit at a point within the tapered portion but adjacent the exit.

RICHARD K. McCONNELL.
